(57) **CLAIM**

I claim the ornamental design for a portable loudspeaker, as shown and described.

DESCRIPTION

FIG. 1 is a perspective view of a portable loudspeaker showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a perspective view of a portable loudspeaker showing a second embodiment of my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The stippling of the end panels in FIGS. 8, 11 and 12 of the second embodiment denotes a portion of the article which has a contrasting appearance relative to the remainder of the article.
